CLASP

Cecil D. Kaufmann, Washington, D. C.

Application May 16, 1940, Serial No. 335,582

4 Claims. (Cl. 24—102)

The invention is directed to clasps of the type adapted to be used, for example, in jewelry of various kinds.

The invention includes a base member which 5 may be equipped with jewels or ornamentations of various kinds when the invention is used for jewelry. Together with the base member there is a bar member mounted to pivot thereon. Between the base member and the bar member, 10 spring means are provided to snap the respective members either into closed or open position with reference to each other, the invention is directed to the construction which produces the snap closing and spring.

Expressed more specifically the invention includes a pivot pin disposed between the base member and the bar member. The pivot pin is fixed to one member and the other member is adapted to rotate thereon. The other member carries the 20 leaf springs, of which there is a plurality in the practice of the present invention. The pivot pin is provided with a flat-sided shank, in the preferred practice of the invention comprising a squared shank with the center of the square coincident with the center of the pivot. One end of each leaf spring is fixed to its incident member, and the springs are directed toward the pivot with their opposite ends resting each on a flat surface of the shank. The terminal edges of the respective springs are disposed on opposite sides of the center of the pin.

With this construction, as the respective members are rotated relative to each other, one spring engages a corner of the shank urging the two 35 members to snap into closed position until the members are rotated to dead center, which in the case of a squared shank is forty-five degrees. That is the spring which extends beyond the center of the pin. The spring which extends short 40 of the center of the pin operates to resist rotation of the two members relative to each other and the resistance increases progressively until the opening rides beyond the edge of the shank. This, in the case of a squared shank, is beyond forty-five 45 degrees. The second spring resists the rotation of the two members relative to each other with increasing resistance until rotation extends well beyond the dead center. At this point the first 50 spring has attained a position in which it urges the two members to continue to rotate and snap into open position. With the sudden cooperation of the other spring the clasp opens rapidly.

The invention is applicable to jewelry of various kinds. It can be used, for example, in cuff links and when so employed it affords a novel

manner of operation to be described more fully in detail hereinafter. The invention finds usefulness in various other types of jewelry, including buckles for braces, belts, etc., bar pins and the like.

The invention finds application to a wide diversity of things, the accompanying drawing being illustrative of some of its uses. In the drawing, to which attention is now directed,

Figure 1 shows a perspective view of the invention, as applied to a cuff link,

Figure 2 is a cross-sectional elevation of the cuff link of Figure 1 in closed position,

Figure 3 is a cross-sectional elevation of the cuff link in partially opened condition,

Figure 4 is a perspective view showing the invention as applied to a buckle,

Figure 5 is a perspective view showing the invention as applied to a bar pin, and

Figure 6 is a cross sectional elevation taken on a plane longitudinally of the pivot pin.

Viewing the cuff link described in Figures 1, 2 and 3, it comprises a base member 11 and a bar member 12 rotatable relative to each other on the pivot pin 13, illustrated in Figure 6. In the practice of the invention shown the pivot pin 13 is fixed to the base member 11 and extends between the prongs 14. The bar member 12 rotates on the pivot pin 13.

The pivot pin is provided with a flat-sided abutment shank 15 which, in the disclosed embodiment, is square with the center of the square coincident with the center of the pin. The shank 15 is preferably housed within the bar 12, as shown. The bar is provided with the leaf springs 16 and 17, which are also preferably housed within the bar in the manner shown. One end of each spring 16 and 17 is fixed to the bar 12, the manner of attachment being unimportant. In the embodiment shown the attaching means comprises a pin 18 riveted to the bar 12, the springs 16 and 17 being attached to the pin 18 by welding or other suitable means. As clearly seen in Figures 2 and 3 the springs 16 and 17 are directed longitudinally of the bar away from the pin 18 and toward the pivot pin 13. The opposite terminal edges 19 and 20 of the respective springs 16 and 17 rest normally on a flat surface of the shank 15, as shown, when the link is in a closed position as shown in Figure 2. The respective terminal edges 19 and 20 are disposed on opposite sides of the center line 13' of the pivot pin 13.

When the bar 12 is rotated relative to the base member 13 to open the cuff link, the spring 17 rests on the surface 21 of the shank 15, which

acts as a cam to urge the bar to snap into the closed position shown in Figure 2. This continues until the bar attains dead center, or has been rotated through 45°. After the bar has been rotated 5 through 45° the cam action of the shank 15 on the spring 17 tends to snap the link in open position.

Meantime the spring 16 tends to hold the link in closed position of Figure 2 and continues to do 10 so until after the bar has been rotated beyond 45°. During the rotation of the bar 12 into open position the terminal edge 19 of the spring 16 is in thrust engagement with the surface 22, and the cam action of the shank 15 on the spring 16 tends 15 to rotate the bar 12 in the counterclockwise direction in Figure 3. The spring 16 continues to urge the bar in closed position while the terminal edge 19 climbs toward the remote edge of the surface 22. The resistance to rotation by the spring 16 20 increases in magnitude until the terminal edge 19 passes the remote edge of the surface 22 and this takes place after the bar 12 has been rotated beyond 45° and is approaching the full 90° open position. This affords a delayed snap in the opening 25 of the link.

The bar member 12 and the base member 11 are disposed away from the pivot 13 to meet at their respective opposite ends 23 and 24. The base member 11, in the embodiment shown, comprises the legs 25 and 26 disposed at an angle with reference to each other. The leg 25 being directed to terminate at the pivot pin 13 and the leg 26 being directed to terminate at the end 23 of the bar 12. The bar 12 and the leg 26 meet 30 at an angle less than 90° when the bar 12 rests abutted against the surface 27 of the base member in closed position.

This construction affords a particular application of the invention to cuff links.

40 Before washing the hands it is desirable to loosen the cuffs and push back the sleeves. Frequently when the hands are quite dirty the cuffs become soiled while the cuff links are being unfastened. Also, in an attempt to prevent soiling 45 the cuff, the link is loosened and left dangling from one buttonhole. There is a great possibility that the link will fall out and be lost.

A cuff link embodying the principles of the present invention may be removed from one buttonhole of the cuff in a manner to facilitate the 50 link to catch the other buttonhole and be securely fastened thereto when the link snaps shut. Thus cuffs can be opened very readily with less danger of the links being lost.

55 This feature is illustrated in Figures 2 and 3 in which the cuff comprises the meeting edges 28 and 29, with the respective buttonholes 30 and 31 spaced away from the edges. The bar passes through the buttonholes 30 and 31 when the link 60 is in closed position. When it is desired to open the cuff without removing the link from the garment the link can be grasped at the bar 26 and pulled away from the buttonhole 31 in the manner illustrated in Figure 3. This will cause the button-hole to actuate the bar 12 to rotate it relative to the base member 11 and it slides out of the button-hole 31. As soon as the end 23 of the bar 12 slips 65 completely out of the buttonhole 31 the bar 12 snaps toward the surface 27 to close the link, fastening the link in the buttonhole 30. This 70 prevents the link from accidentally falling out of the buttonhole and becoming lost.

When it is desired to open the cuff while the hands are very dirty, pressure of the finger against

the end 24 of the base member will cause the link to open sufficiently to slip out of one side of the cuff. As soon as the bar leaves one buttonhole the link will automatically snap to closed position.

5 In Figure 4 the invention is shown as applied to a buckle, for example, for a belt 35. The buckle comprises the base member 36 and the bar member 37 pivoted at 38 and operative in the same manner as the cuff link. The rings 39 and 40 are attached to the cleats 41 and 42 respectively 10 which project from the base member 36. It will thus be seen that the load is carried by the cleats 41 and 42 and is not carried by the bar member 37. The base member 36 provides the face of the buckle. 15

In Figure 5 the invention is disclosed as applied to a bar pin in which the bar 44 functions to house the spring and is pivoted on the pivot pin 45 which is fixed to the stick pin 46. The rest 47, attached to the bar 44, engages the pin 46 when 20 in closed position.

The invention having been described in detail in a plurality of embodiments, it is now pointed out that it is not limited to the structures shown but that the accompanying claims determine the scope 25 of the invention.

What I claim is:

1. A clasp for jewelry or the like comprising a base member and a bar member mounted pivotally thereon, a flat-sided abutment piece fixed to 30 one member, a plurality of leaf springs fixed to the other member one end of each leaf spring being attached, the leaf springs being directed away from the point of attachment toward the abutment piece and one end of each spring being respectively disposed on opposite sides of the center of the abutment member.

2. A clasp for jewelry or the like comprising a base member, a bar member, and a pivot pin therebetween, the pivot pin providing a flat-sided 40 shank, a plurality of leaf springs coacting with the shank, the pivot being attached to one member with the other member rotating thereon, one end of each leaf spring being attached to the other member and directed toward the pivot with the 45 opposite end resting on the flat-sided shank, the terminal edges of respective springs being disposed on opposite sides of the center of the pivot.

3. A clasp for cuff links comprising a base member, a bar member, and a pivot pin therebetween, 50 the base member and bar member being directed away from the pivot pin disposed with their respective opposite ends making an angle less than a right angle, the pivot pin providing a flat-sided shank, a plurality of leaf springs coacting with 55 the shank, the pivot being attached to one member with the other member rotating thereon, one end of each leaf spring being attached to the other member and directed toward the pivot with the opposite end resting on the flat-sided shank, 60 the terminal edges of respective springs being disposed on opposite sides of the center of the pivot.

4. A clasp comprising a pair of cooperating clasping members, a pivot fixed with respect to 65 one member the other member being hinged on said pivot, one of said members having a cam fixed thereto coaxial with said pivot, a pair of parallel leaf springs carried by the other member embracing said cam on opposite sides and terminating on opposite sides of the axial plane of 70 said cam perpendicular to said springs.
